INVENTORS:

UNITED STATES PATENT OFFICE.

THOMAS M. KNOWLAND AND ARTHUR DRECHSLER, OF WATERTOWN, MASSACHUSETTS,
ASSIGNORS TO HOOD RUBBER COMPANY, OF WATERTOWN, MASSACHUSETTS, A
CORPORATION OF MASSACHUSETTS.

LASTING JACK.

Application filed December 13, 1927. Serial No. 239,770.

This invention relates to an improvement in lasting jacks.

The object of the invention is to provide a lasting jack which will firmly grasp the last and which can be manipulated by the operator to turn the last into a variety of different positions, so that the shoe which is being made upon the last may be conveniently operated upon.

10 The invention consists in the combination and arrangement of parts set forth in the following specification and particularly pointed out in the claims thereof.

Referring to the drawings:

15 Figure 1 is a side elevation partly in section of our improved lasting jack, a last being shown in section mounted thereon.

Fig. 2 is a sectional elevation taken on line 2—2, Fig. 1.

20 Fig. 3 is an underneath plan of the carrier forming a part of the last holder.

Fig. 4 is a sectional plan broken away taken on line 4—4, Fig. 1.

25 Fig. 5 is a side elevation of the lasting jack broken away, with a last shown in section mounted thereon.

Fig. 6 is a detail side elevation of the slide.

Fig. 7 is a front elevation of the slide.

Fig. 8 is a top plan view of the slide.

30 Fig. 9 is an underneath plan view of the slide.

Like numerals refer to like parts throughout the several views of the drawings.

In the drawings, 10 is a stationary member adapted to be fastened to a suitable support. 11 is a bracket which is rotatably mounted upon a stud 12 having screw-threaded engagement with the stationary member 10.

35 A spring 13 is positioned in a recess 14 in the bracket 11 and bears at one end against the head 15 of the stud 12 and at the other end against the bottom of the recess 14, thus forcing the bracket against the stationary member 10 with a yielding pressure.

40 The face 16 of the bracket is serrated and bears against a similar serrated face on the stationary member 10, so that as the bracket is turned to different angles it will be held against accidental displacement upon the stationary member by the spring 13 which will hold the serrated faces on the bracket and stationary member in contact with each other.

The bracket 11 is bifurcated at its outer end to receive a connecting member 17 which is rotatably mounted upon a stud 18 fast to one arm 19 of the bifurcated end of the bracket 11. The connecting member is provided with a recess 20 in which is positioned a spring 21 bearing at one end thereof 55 against the bottom of the recess 20 and at the other end against the head of the stud 18, thus forcing the connecting member against a friction washer 22 interposed between it and the arm 19. It will thus be seen that the connecting member 17 can be rotated upon the stud 18 and is held against accidental displacement by the spring 20 and the friction washer 22.

55 A last support 23 is rotatably mounted upon the connecting member 17 and consists of a carrier 24 and slide 25. The carrier 24 has fastened thereto a stud 26 which is rotatably mounted in the connecting member 17 and has a spring 27 interposed between 60 the head of said stud and the bottom of a recess 28 provided in the connecting member 17 and in which the spring 27 is positioned.

65 A friction washer 29 is interposed between 70 the connecting member 17 and the carrier 24, so that the last support as a whole can be rotated about a vertical axis and the same is held against rotation about its vertical axis by a latch 30 pivoted at 31 to the carrier 24 and provided with a tooth 32 which projects into a recess 33 in the connecting member 17. The latch 30 is provided with notches 34 and 35 which are adapted to be engaged by a spring pawl 36, so that the 75 latch 30 may be held in position to lock the carrier against rotation upon the connecting member 17, or it may be positioned out of locking engagement therewith.

80 When in the position illustrated in Fig. 1, the carrier is locked against rotation upon the connecting member. If, however, the latch is thrown downwardly, so that the pawl 36 engages the notch 34, then the carrier will be out of locking engagement with 85 the connecting member.

85 When in the position illustrated in Fig. 95 1, the carrier is locked against rotation upon the connecting member. If, however, the latch is thrown downwardly, so that the pawl 36 engages the notch 34, then the carrier will be out of locking engagement with 90 the connecting member.

95 The slide 25, illustrated in detail in Figs. 6, 7, 8 and 9, consists of a base 37 provided with a slot 38 and a shank 39 which extends 100 upwardly from the base and is screw threaded to receive a nut 40. The shank 39

105

is rotatable and slidable in the carrier 24 and a spring 41 positioned in a recess 42 in the carrier 24 bears against the nut 40 at its upper end and against the bottom of the recess 42 at its lower end, thus holding the slide, consisting of the shank 39 and base 37, upwardly in the position illustrated in Fig. 1.

The base 37 is provided with a cam 43 which is held against a cam-shaped recess 44 in the carrier 24. The cam 43 consists of V-shaped projections which are integral with the base 37 and are positioned on diametrically opposite sides of the shank 39, so that when the slide is rotated about a vertical axis the cam projections 43 riding out of the recesses 44 provided in the under face of the carrier 24 will move the slide 25 downwardly as a whole, compressing the spring 41. When this happens a pair of levers 45 and 46, which are pivoted at 47 upon the base 37, will be rocked upon their pivot by a spring 48 interposed between the upper ends of the levers 45 and 46 and thus cause the lower ends of the levers, which constitute jaws 49 and 50, to move toward each other and thus release the last 51, so that it can be removed from the jaws 49 and 50. In order to grip the last securely, the jaws 49 and 50 are serrated at 52 and 53 and project downwardly into the slot 38 of the base 37.

The upper ends of the levers 45 and 46 are bevelled at 54 and 55 respectively forming cam-shaped surfaces which engage like cam-shaped or bevelled surfaces 56 and 57 on the side wall 58 of a recess 59 provided in the lower side of the carrier 24 and into which recess the upper portion 60 of the base 37 projects.

The general operation of the lasting jack is as follows:—The last 51 is forced on to the jaws 49 and 50 when the jaws have been moved toward each other by the spring 48, as hereinbefore described. At this time the cam-shaped projections 43 on the base 37 are riding against the surface 61 at the top of the recess 59. The last and base 37 are then rotated until the cam-shaped projections 43 snap into the cam-shaped recesses 44 on the carrier, by reason of the action of the spring 41 which moves the slide 25 upwardly. As the slide 25 moves upwardly the bevelled upper ends of the levers 45 and 46 engage the bevelled inner surfaces 54 and 55 on the carrier 24 and this forces the jaws 49 and 50 apart causing them to tightly grip the last 51. Now the last may be rotated about a vertical axis by rotating the carrier 24 and the stud 26 on the connecting member 17, or it may be rotated about a horizontal axis, namely, the stud 18, or it may be rotated about another horizontal axis, namely, the stud 12. Thus it will be seen that the last can be rotated into any desired position about the different axes of rotation provided

in the lasting jack, and it may be locked against rotation about the axis of 26 by the latch 30.

It will be understood that by rotating the last and the jaws 49 and 50, together with the slide 25, consisting of the base 37 and shank 39, the jaws may be operated to grip or to release the last according to the direction in which the last is rotated.

We claim:

1. A last holder for a lasting jack having, in combination, a carrier, oppositely disposed jaws rotatably mounted on said carrier, and means to move said jaws relatively to each other due to the relative rotation of said carrier and jaws, whereby a last may be gripped or released by said jaws.

2. A last holder for a lasting jack having, in combination, a carrier, oppositely disposed jaws rotatably mounted on said carrier, and means to move said jaws away from each other due to the rotation of said jaws on said carrier in one direction and toward each other when rotated on said carrier in the opposite direction, whereby a last may be gripped or released by said jaws.

3. A last holder for a lasting jack having, in combination, a carrier, a slide comprising a shank rotatably mounted on said carrier and a base fixed relatively to said shank with a cam-shaped surface thereon bearing against a cam-shaped surface on said carrier, and a spring in said carrier holding said cam-shaped surfaces in contact, and a pair of jaws pivoted to the base and positioned in a slot provided therein, and means to move said jaws relatively to each other when the slide is rotated on the carrier, whereby a last may be gripped or released by said jaws.

4. A last holder for a lasting jack having, in combination, a carrier, a slide comprising a shank rotatably mounted on said carrier and a base fixed relatively to said shank with a cam-shaped surface thereon bearing against a cam-shaped surface on said carrier, and a spring in said carrier holding said cam-shaped surfaces in contact, a pair of levers constituting jaws pivoted to the base and positioned in a slot provided therein, and means to move said jaws toward each other when the slide is rotated in one direction and away from each other when the slide is rotated in the opposite direction.

5. A last holder for a lasting jack having, in combination, a pair of vertical and oppositely disposed levers, a vertical slide, a pivot on said slide to which said levers are pivoted, the lower portions of said levers constituting jaws, the upper ends of said levers extending above said pivot, a carrier upon which said slide is slidably and rotatably mounted, and means to cause said levers to rock upon their pivot to move said

jaws relatively to each other when the slide is rotated upon the carrier.

6. A last holder for a lasting jack having, in combination, a pair of vertical and oppositely disposed levers, a vertical slide, a pivot on said slide to which said levers are pivoted, the lower portions of said levers constituting jaws, the upper ends of said levers extending above said pivot, a carrier upon which said slide is slidably and rotatably mounted, and means to cause said levers to rock upon their pivot to move said jaws away from each other when the slide is rotated in one direction and toward each other when the slide is rotated in the opposite direction.

7. A last holder for a lasting jack having, in combination, a pair of vertical and oppositely disposed levers, a vertical slide, a pivot on said slide to which said levers are pivoted, the lower portions of said levers constituting jaws, the upper ends of said levers extending above said pivot, a carrier upon which said slide is slidably and rotatably mounted, and means to cause said levers to rock upon their pivot to move said jaws relatively to each other when the slide is moved longitudinally thereof.

8. A last holder for a lasting jack having, in combination, a pair of vertical and oppositely disposed levers, a vertical slide, a pivot on said slide to which said levers are pivoted, the lower portions of said levers constituting jaws, the upper ends of said levers extending above said pivot, a carrier upon which said slide is slidably and rotatably mounted, and means to cause said levers to rock upon their pivot to move said jaws away from each other when the slide is moved longitudinally thereof in one direction and toward each other when the slide is moved longitudinally thereof in the opposite direction.

9. A last holder for a lasting jack having, in combination, a pair of vertical and oppositely disposed levers, a vertical slide, a pivot on said slide to which said levers are pivoted, the lower portions of said levers constituting jaws, the upper ends of said levers extending above said pivot, a carrier upon which said slide is slidably and rotatably mounted, means to cause said levers to rock upon their pivot to move said jaws away from each other when the slide is moved longitudinally thereof in one direction and toward each other when the slide is moved longitudinally thereof in the opposite direction, and means to move said slide longitudinally thereof when it is rotated upon the carrier.

10. A last holder for a lasting jack having, in combination, a pair of vertical and oppositely disposed levers, a vertical slide, a pivot on said slide to which said levers are pivoted, the lower portions of said levers

constituting jaws, the upper ends of said levers extending above said pivot, a carrier upon which said slide is slidably and rotatably mounted, a spring to cause said jaws to move toward each other when the slide is moved longitudinally thereof in one direction, and a cam on said carrier to move said jaws apart when the slide is moved longitudinally thereof in the opposite direction.

11. A last holder for a lasting jack having, in combination, a pair of vertical and oppositely disposed levers, a vertical slide, a pivot on said slide to which said levers are pivoted, the lower portions of said levers constituting jaws, the upper ends of said levers extending above said pivot, a carrier upon which said slide is slidably and rotatably mounted, a spring to cause said jaws to move toward each other when the slide is moved longitudinally thereof in one direction, a cam on said carrier to move said jaws apart when the slide is moved longitudinally thereof in the opposite direction, and means to move said slide longitudinally thereof when it is rotated upon the carrier.

12. A last holder for a lasting jack having, in combination, a pair of vertical and oppositely disposed levers, a vertical slide, a pivot on said slide to which said levers are pivoted, the lower portions of said levers constituting jaws, the upper ends of said levers extending above said pivot, a carrier upon which said slide is slidably and rotatably mounted, a spring to cause said jaws to move toward each other when the slide is moved longitudinally thereof in one direction, a cam on said carrier to move said jaws apart when the slide is moved longitudinally thereof in the opposite direction, a spring to move said slide in one direction, and a cam to move the slide longitudinally thereof in the opposite direction when the slide is rotated upon the carrier.

13. A lasting jack having, in combination, a last holder embodying a carrier, oppositely disposed pivotally mounted jaws rotatably mounted on said carrier, and means fixed relatively to said carrier and adapted to be engaged by said jaws when they are rotated on said carrier whereby said jaws may be rocked upon their pivots.

14. A last holder for a lasting jack having, in combination, a carrier, oppositely disposed pivotally mounted jaws rotatably mounted on said carrier, means fixed relatively to said carrier and adapted to be engaged by said jaws when they are rotated on said carrier, whereby a last may be gripped or released by said jaws, a connecting member upon which said carrier is rotatably mounted, means to lock said carrier against rotation thereon, and a bracket upon which said connecting member is rotatably mounted.

15. A last holder for a lasting jack hav-

ing, in combination, a carrier, oppositely disposed jaws rotatably mounted on said carrier, means to move said jaws relatively to each other when they are rotated on said carrier, whereby a last may be gripped or released by said jaws, a connecting member upon which said carrier is rotatably mounted, means to lock said carrier against

rotation thereon, a bracket upon which said connecting member is rotatably mounted, and a stationary member upon which said bracket is rotatably mounted. 10

In testimony whereof we have hereunto set our hands.

THOMAS M. KNOWLAND.
ARTHUR DRECHSLER.
